UNITED STATES PATENT OFFICE.

EUGENE L. HOWE, OF CLEVELAND, OHIO.

DESIGN FOR A HARNESS-SNAP.

SPECIFICATION forming part of Design No. 21,398, dated **March 15, 1892.**

Application filed January 22, 1892. Serial No. 418,964. Term of patent 14 years.

To all whom it may concern:

Be it known that I, EUGENE L. HOWE, of Cleveland, in the county of Cuyahoga and State of Ohio, have invented a new and original Design for Harness-Snaps, of which the following is a full, clear, and exact description, reference being had to the accompanying drawings, forming part of this specification, in which—

10 Figure 1 shows in plan view a harness-snap embodying the design. Fig. 2 is a side view thereof.

Like symbols of reference indicate like parts in each figure.

15 The design consists in a harness-snap having substantially the shape shown in the accompanying drawings, and hereinafter described.

In the drawings, 2 represents the buckle portion of the snap.

20 5 represent the body of the snap, having

a curved hook-shaped portion 4 and having converging outlines extending from the buckle portion toward the barrel hereinafter mentioned.

25 3 is a straight cylindrical barrel superposed on the body 5 and having a longitudinally-projecting tongue 6, which meets the end of the hook. The part 3 has cylindrical outline distinct from the outline of the body 5, which projects laterally therefrom, so as to be visible when the article is viewed in plan, as in Fig. 1.

I claim—

30 The design for harness-snaps, substantially as herein shown and described.

In testimony whereof I have hereunto set my hand this 16th day of January, A. D. 1892.

EUGENE L. HOWE.
